UNITED STATES PATENT OFFICE

LORENZO ARRANZ, OF NEW YORK, N. Y.

PLATEN-ADJUSTING DEVICE

Application filed May 19, 1928. Serial No. 279,104.

This invention relates to typewriter letter spacing devices, and particularly to fractional letter spacing mechanism.

On operation of the keys of a typewriter to produce impressions on a work sheet carried by the cylindrical platen, the type bars are effective to move a universal bar to cause the platen to be fed in letter space direction an equal distance for each impression or character typed, and as the platen is also revolvable in line space direction an equal distance for each line written, the result is that the type faces strike the same point on each line on second and subsequent revolutions of the platen, thereby causing indentations or holes to be made in the surface of the platen, which is usually of rubber, with the result that blurring of the characters produced on the work sheet is caused.

The primary object of this invention is the provision of means for moving the platen at predetermined intervals, relatively to the type bars, so that the impressions will be produced on a different point of the platen after each operation of said means, thereby causing clear impressions to be made and preventing the formation of holes in the material of the platen.

As the work sheet is usually held in movable contact with the surface of the platen by co-operating feed rolls, which are releasable by a feed roll operating lever for insertion or removal of the work sheet, it is another object of my invention to utilize the feed roll lever for operating my fractional letter space device. It will therefore be seen that on insertion of each work sheet the platen is automatically so moved that the impressions are received on the sheet opposite a different point of the surface of the platen, without necessitating any attention by the typist.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a fragmentary top plan view of a typewriter with my invention attached to the feed roll release lever thereof.

Figure 2 is an enlarged vertical longitudinal sectional view taken on the line 2—2 of Figure 1.

Figure 3 is a perspective view, in separate relation, of a roller carrying ratchet wheel and a disk having a lateral cam face to co-operate with the rollers.

Figure 4 is an elevational view of the camming disk per se.

Figure 5 is an elevational view partly sectional on the line 5—5 of Figure 1.

Figure 6 is a perspective view of the operating lever for the ratchet wheel and the parts of a pawl in a separate relation.

Referring particularly to the drawing, the numeral 10 designates a cylindrical platen which, by hand wheels 11 rigidly mounted on an axle 12 or by line space mechanism generally represented at 13, is revolvable for feeding, in co-operation with front and rear pressure rolls 14, a sheet of paper on which the imprint of the usual types is received. The axle 12 is journaled in end plates 15 of the platen frame 16 which is movable laterally in letter feed and return direction, while the pressure of the feed rolls on the work sheet may be applied and released by a lever 17. So far the mechanism described may be like that found in any well-known typewriter.

Revolutely mounted by a hub 18 on the platen shaft 12, I provide a ratchet wheel 19 having a flange 20, the exterior periphery of which is formed with appropriate ratchet teeth 21, while three radially disposed pins 22 projecting from the inner face of said flange carry rollers 23 for a purpose to presently appear.

Fixedly mounted on the right hand platen frame 15, as by a bracket 24 with screws 25, and having a hub 26 in which the shaft 12 is revolvable, there is a disk 27 the flange 28 of which is formed with three equally projecting cam points 29 midway between which are recesses 30, thus forming a curved cam rib, the face of which forms a track for said rollers 23.

The feed roll release lever 17 is pivoted on the platen frame as at 31 and has in its lower terminal an aperture 32 to receive the stem of a screw 33 by which a pawl 34 is pivoted on said lever, the screw being secured in a tapped hole 35 in the angularly turned arm 36 of said pawl. The end of the pawl is formed with an upturned tooth 37 and a central web having an opening 38 therein to receive the pin 39 of a movable detent 40, the ears 41 of which are adapted to hingedly embrace said web, while one end of a leaf spring 42 is attached to the detent 40 to normally hold the same in position against the ratchet teeth as will be hereinafter explained.

Preferably attached to the platen frame 16, is a bracket 43 formed with two angularly turned ears 44 between which a compression spring 45 is located on a detent pin 46 to strongly urge one end of the latter against a tooth of the ratchet wheel. The pawl 34 is supported as at 47, while the lever 17 normally rests against the rear of the platen frame represented at 48. To accommodate the invention, the platen is urged against a friction washer 49 by a spring 50, the shaft 12 being capable of limited sliding movement through the plates 15.

It will readily be seen that, in practice, the ratchet wheel 19 is individually revolvable on operation of the lever 17, which, when advanced to the dot and dash position shown in Figure 5, draws the pawl 34 rearwardly, the detent 40 at the same time contacting with a tooth 51 to move a tooth 52 past the pin 46, the latter then resting against a tooth 53 to hold said ratchet wheel fast. On return of the lever to its normal position the spring pressed detent 40 slides over a tooth 54 to rest against another tooth 55.

As there are a greater number of teeth on the ratchet wheel than on the usual line space wheel of the machine, it will be seen that the action of the lever 17 also rotates the wheel 19 a fractional part of a line space, and as there is an inclination from vertical of the face of the cam rib, it will be evident that there is a limited horizontal travel or fractional letter space movement of the platen, while the wheel 19 is rotated one tooth interval and while the rollers 23 move a corresponding distance over the cam face. This fractional longitudinal travel of the platen is to the right, urged by the spring 50, as a roller 23 moves from a projection 29 to a recess 30; and to the left, urged by the lever 17, acting through the wheel 19 against the action of said spring, as a roller 23 moves from a recess to a projection. The ratchet wheel may have about sixty teeth, while the number of rollers may be as desired, one roller alone being sufficient within the scope of the invention. The depth of the curve 65 of the cam face, measured horizontally from

a recess to a projecting point may be about equal to two letter spaces.

As the ratchet wheel 19, against which the platen is urged, is represented in the present instance as having 60 teeth, and as the cam face has six rising and falling or inclined surfaces, each corresponding to a distance of ten teeth, while the longitudinal friction drive of the platen is about two letter spaces, it follows that each fractional step of the platen, when the lever 17 is operated to revolve said wheel one tooth space, is one fifth of a letter space. Normally said lever is operated, and therefore the platen automatically adjusted for wear distribution of its surface between letter spaces, each time the feed rolls 14 are released to insert a work sheet. The longitudinal platen movements are, of course, to the right and to the left alternately, as the rollers descend and ascend the inclined surfaces of the cam while the rotary movement of the wheel 19, which carries the rollers, is always in one direction, as indicated by the arrow in Figure 5.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A fractional letter spacing device for a typewriter comprising a platen and its shaft and a frame therefor, a disk rigidly mounted on said frame wherein the shaft of the platen is slidable, a curved cam rib on said disk, and a revolvable ratchet wheel having rollers thereon for travelling along said cam rib to slide the platen and shaft limitedly.

2. A fractional letter spacing device for a typewriter comprising a revolvable platen and its shaft and a frame therefor, a disk rigidly mounted on said frame wherein the shaft of said platen is longitudinally movable, a lateral cam rib on said disk having a projection thereon, and a revolvable ratchet wheel carrying rollers for traveling past said projection to move the platen longitudinally.

3. A fractional letter spacing device for a typewriter comprising a longitudinally movable platen having a shaft and a platen frame wherein said shaft is revolvable, a fixed disk wherein said shaft is revolvable, a cam rib on said disk having a recessed face, a separately revolvable ratchet wheel on said shaft adjacent the disk, and rollers on said ratchet wheel adapted for movement over the recess of said cam face to move the platen longitudinally a predetermined distance upon turning of said ratchet wheel.

4. A fractional letter spacing device for a typewriter comprising a revolvable platen

and its shaft and a frame therefor in which the platen is longitudinally movable, a fixed disk on said frame wherein the shaft of said platen is revolvable, a curved cam surface on said disk, a revolvable ratchet wheel having an annular flange, the cam face of said disk located internally of said flange, and a plurality of rollers carried by said flange internally thereof for traveling on 5 said cam face to move the platen longitudinally on turning of said ratchet wheel.

5. A fractional letter spacing device for a typewriter comprising in combination a platen and its shaft and a frame therefor in 10 which the platen is longitudinally movable, pressure rolls co-operating with the platen and a release lever for said rolls, a disk rigidly mounted on said frame wherein the shaft of the platen is revolvable, a ratchet wheel 15 having a flange and teeth peripherally thereof, rollers carried by said flange internally thereof, said disk having a rising and falling cam face on which said rollers are adapted to travel to fractionally move the platen endwise 20 between letter spaces, and a pawl connecting said lever with the teeth of said ratchet wheel to automatically rotate the latter on release of said feed rolls.

6. A fractional letter spacing device for a 25 typewriter comprising in combination a platen and its shaft and a frame therefor in which the platen is longitudinally movable, pressure rolls co-operating with the platen, a release lever for said rolls, a disk rigidly 30 mounted on said frame wherein the shaft of the platen is revolvable, a ratchet wheel having a flange and teeth peripherally thereof, rollers carried by said flange internally thereof, said disk having a rising and falling cam 35 face on which said rollers are adapted to travel to fractionally move the platen endwise between letter spaces, a pawl automatically operated by said lever on release of said feed rolls, and a compression spring on 40 the shaft of the platen to urge the latter endwise to maintain connection between said rollers and said cam face.

7. A fractional letter spacing device for a typewriter comprising a platen frame, a 45 shaft having a platen fixed thereto and longitudinally slideable in said frame, a cam element fixed to said frame through which the shaft is slideable, and a separately revolvable device on said shaft cooperating with 50 said cam element to slide the platen and its shaft longitudinally.

8. A fractional letter spacing device for typewriters comprising a machine having a 55 platen frame, a shaft having a platen fixed thereto and longitudinally slideable in said frame, a cam element fixed to said frame and having an undulating surface, and a member on said shaft, between said platen and 60 said cam element, provided with rollers, said

rollers engaging with said undulating surface to slide the platen laterally.

9. In a typewriting machine having a longitudinally slideable shaft and a platen fixed thereto, a fixed cam member having an undulating surface, spring means for sliding the platen with its shaft in one direction, manually operable means for sliding said platen with its shaft in the opposite direction, said latter means comprising a rotatable wheel turnable on said shaft with respect to the platen, and rollers carried by said wheel for riding over said undulating cam surface. 70

10. In a typewriting machine having a longitudinally slideable shaft and a platen 75 fixed thereto, a fixed cam member having an undulating surface, spring means for sliding the platen with its shaft in one direction, manually operable means for sliding said platen with its shaft in the opposite direction, said latter means comprising a ratchet wheel 80 revolvably mounted on said shaft, rollers carried by said wheel for riding over said undulating cam surface, and manipulating pawl mechanism correlated with said ratchet wheel for imparting predetermined turning movement thereto in one direction. 85

In testimony whereof I have affixed my signature.

LORENZO ARRANZ.
